UNITED STATES PATENT OFFICE

CARL PETERSON, OF JAMAICA PLAIN, MASSACHUSETTS, ASSIGNOR TO GEORGE LAWRENCE, OF CAMBRIDGE, MASSACHUSETTS

SPRING-LEAF-FORMING MECHANISM

Application filed July 28, 1927. Serial No. 208,967.

My invention aims to provide improvements in spring-forming machines and more particularly to that part of the machine used for bending a spring leaf to a desired form.

5 In the drawings, which illustrate a preferred embodiment of the invention:—

Figure 1 is an elevation showing the lower portion of a spring leaf-bending and tempering machine, the upper part of the machine 10 being omitted;

Fig. 2 is an enlarged detail elevation showing a portion of the cable, the center support, one of the end supports and a portion of the supporting frame;

15 Fig. 3 is a detail view, being partly in cross-section to show one of the pulleys and the means for adjusting it upon its carrying sleeve;

Fig. 4 is a section on the line 4—4 of Fig. 20 3 showing the supporting means for the cables in cross-section, the pulleys and equalizing means in elevation;

Fig. 5 is a section through a portion of one 25 of the cables, the stud strand being shown in elevation; and

Fig. 6 is a section taken on the line 6—6 of Fig. 2 showing one of the presser members.

Referring to the embodiment of my invention, as illustrated by the drawings, I have 30 shown a spring leaf-forming mechanism which may be used in connection with any type of machine to which it may be adapted.

For the purpose of illustration, I have shown the forming mechanism as it is used in connection with a machine substantially the same as shown and described in my co-pending application, Serial No. 125,113, filed July 26, 1926.

I have shown only enough of that machine to enable those skilled in the art to 40 understand the operation of the present invention.

For the purposes of the present application, I have shown a portion of the frame including the upright parts 3, the sliding cross-bars 5, 6 and 7, the toggle link arrange-

ment 19, the strips 21 connecting the bars 5 and 7, a portion of the rack rod 22, the links 23^a connecting the toggles 19^a with the rack rod 22, the block 56, the hand wheels 54, threaded shafts 52 and the die means carried by the lower cross-bar 7. The die means include the adjustable dies 9, the ratchet wheels 14 and releasing lever 17. The oil tank 1, into which the spring, when formed, is lowered, is also shown.

The numerals used in the above description correspond to the numerals used in designating the same parts described in the above mentioned application.

Referring now to my invention, as intended to be covered by the present application, I have shown cable means mounted upon the cross-bar 6. This cable means includes two parallelly arranged cables A having their ends secured in sleeves 60, the sleeves being secured to equalizing members 61 pivoted upon the sliding pins 62 mounted in the blocks 63 secured to the cross-bar 6, as best shown in Figs. 2 and 4. Each pin 62 has a spring 64 associated therewith and interposed between the plate 65 and the washer 66 to provide spring cushions. Thus the cables A are resiliently mounted upon the cross-bar 6. The nuts 67 threaded upon the upper ends of the pins 62 provide means for varying the tension of the springs.

The cables A extend from one equalizing member 61 around pulleys 68, supported by the bracket 69 hung from the cross-bar 6 (Fig. 1), then to the centrally located supporting element 70 where two connections are made between each cable and the element 70. The cables then extend around another set of pulleys 68^a, supported by the bracket 69^a, to the other equalizing member 61. The brackets 69 and 69^a are braced by the link pieces 71, as shown in Figs. 2 and 3.

Each cable A comprises the stranded steel cable 72 having arranged thereon a series of ball-like members of two sizes. The larger

ball-like members 73 make spaced joint contact with the spring leaf B (Fig. 1) and the small ball-like members 74 provide spacers and have their ends fitted into the larger members 73 (Fig. 5) to provide ball and socket joints. The steel cable is flexible, and the ball and socket joints between the ball-like members 73 make it possible to bend the cables A into any desired shape.

Some spring leaves must be provided with concave portions adjacent their ends and in order to press the cables A against the spring leaf B to press it into the depressions, provided by the die means, I have provided the shoes or pressers 75. These pressers are pivotally secured to rods 76 slidably mounted in the blocks 77 secured to the cross-bar 6 and springs 78 are provided to press the pressers toward the cables A, as shown in Figs. 1 and 2. The blocks 77 are provided with the ears 79 which make threaded engagement with the shafts 52 to permit longitudinal adjustment of the pressers 75.

The central supporting element 70 is slidably mounted in the carrying part 58 secured to the cross-bar 6, as shown in Fig. 2. Two of the larger ball-like members 73 in each cable assembly are provided with shank portions 73^a connected through pin and slot means to the supporting element 70, as shown in Fig. 2.

The pulleys 68 and 68^a are mounted upon sleeves 81 (Fig. 4) and the pulleys in the set 68 and the set 68^a are slideable toward and away from each other to adapt the cables A to various width spring leaves. The adjustment of the pulleys is secured by means of yokes 82 mounted upon right and left-hand threaded shafts 83 secured in the brackets 69 and 69^a. By turning the wrench-receiving portion 83^a of the threaded shafts 83 (Fig. 4) in one direction or the other the adjustment of the cables may be made. The yokes fit into the grooves in the pulleys so that movement of the yokes provides for the movement of the pulleys.

In operating the mechanism above described, I first adjust the die members 9 to the desired form to which the spring leaf is to be bent. The die members 9 may be roughly adjusted to a templet by lifting them by hand and then securing a more perfect adjustment to the templet by rotating the ratchet wheels 14 in substantially the same manner as more fully set forth and described in my co-pending application above referred to. After the die members 9 have been adjusted to the form of the templet, the templet may be removed and the die members will present a form to which a spring leaf is to be shaped. Next I place the hot spring leaf B upon the die means and set the machine in operation, so that the rack rod 22 will operate the toggle means to move the cross-bar 6 toward the die means. Any suitable means may be used

to drive the rack rod. During this movement of the bar 6, the cable means is brought into contact with the spring leaf B. As the bar 6 continues toward the die means the cable means bends the spring leaf to conform to the shape of the die means. During this operation, the cable means is drawn tightly against the spring leaf and the springs 64 yield to prevent breaking of the cables A and the equalizing members 61 may rock to equalize the strain on both cable assemblies.

The universal movement of the ball-like members 73 and 74 permits them to conform exactly to the shape of the die means and the contact made between the large ball-like members 73 and the spring leaf B is only at spaced points. Thus, when the spring is lowered into a oil in the tank 1 for tempering, practically all the upper surface of the spring leaf is exposed to the action of the oil.

The ball-like members do not extend the entire length of each of the steel cables and, therefore, springs 84 are interposed between the ball-like members and the equalizing means 61 (Figs. 3 and 4) to keep them in contact.

If a spring is to be formed with the concave portions at the ends, as shown in Figure 1, the shoes or pressers 75, which are wide enough to span both cables A (Fig. 6) and which engage the larger ball-like members 73, press the cables into the desired shape. The heavy springs 78 are compressed during the pressing together operation and are strong enough to overcome the pull on the cables by the springs 64.

The above described improvements in spring-forming means are simple in operation and durable and the peculiar construction and mounting of the cable means is exceedingly efficient in operation, while at the same time providing the least amount of interference possible with the tempering of the spring leaves.

While I have shown and described a preferred embodiment of my invention it should be understood that I do not wish to be limited thereby, my invention being best defined in the following claims.

Claims:

1. A spring leaf forming mechanism including a series of independently adjustable elements providing a form to which a spring leaf may be shaped, and cable means mounted for pressing the spring leaf to the shape of the form provided by said elements, said cable means having a plurality of ball and socket elements carried thereby and arranged to make spaced contact with the spring leaf thereby to expose a maximum of the spring leaf surface.

2. A spring leaf forming mechanism including means providing a form to which a spring leaf may be shaped, and cable means mounted for pressing the spring leaf to the

- shape of the means providing the form, said cable means having a plurality of ball-like members adapted to make only spaced point contacts with the spring leaf, thereby to expose a maximum of the spring leaf surface. 5
3. A spring leaf forming mechanism including means providing a form to which a spring leaf may be shaped, and cable means mounted for pressing the spring leaf to the shape of the means providing the form, said cable means having a plurality of ball-like members making ball and socket contact for universal movement relative to each other. 10
4. A spring leaf forming mechanism including means providing a form to which a spring leaf may be shaped, and cable means mounted for pressing the spring leaf to the shape of the means providing the form and a yieldably mounted presser member slidable 20 longitudinally relative to said cable means and adapted to engage the cable means to press the spring leaf into a depression provided by the form means. 25
5. A spring leaf forming mechanism comprising, in combination, a frame, a pair of cross-bar members supported by said frame, a series of independently adjustable elements carried by and adjustable relative to one of said cross-bar members to provide a form 30 against which a spring leaf may be formed, yieldable cable means resiliently mounted upon the other of said cross-bar members for pressing the spring leaf against said form, said cable means including a wire cable and a series of ball and socket members carried by said wire cable and means for moving one of said cross-bar members relative to the other. 35
6. A spring leaf forming mechanism comprising, in combination, a frame, a pair of cross-bar members supported by said frame, means carried by and adjustable relative to one of said cross-bar members to provide a form against which a spring leaf may be 40 pressed, a pair of cables supported by the other of said cross-bars for pressing the spring leaf against said form, yieldable means mounted on the same cross-bar member as said cables and secured to said cables and adjustable means for laterally adjusting said cables toward and away from each other. 45
7. A spring leaf forming mechanism comprising, in combination, a frame, a pair of sliding cross-bar members supported by said frame, means carried by and adjustable relative to one of said cross-bar members to provide a form against which a spring leaf may be formed, a pair of cables for pressing the spring leaf against said form and equalizing 50 means connected between the ends of said cables and the other of said cross-bars to equalize the pressure on said cables when contacted with the spring leaf. 55
8. A spring leaf forming mechanism comprising, in combination, a frame, a pair of 60 sliding cross-bar members supported by said frame, means carried by and adjustable relative to one of said cross-bar members to provide a form against which a spring leaf may be formed, a pair of cables for pressing the spring leaf against said form, bracket means secured to the other of said cross-bars and carrying pulleys supporting said cables, resilient means interposed between said cables and said last mentioned cross-bar, means for adjusting said pulleys toward and away from each other axially to adjust said cables to various width spring leaves and equalizing means for equalizing the pressure on said cables. 70
9. A spring leaf forming mechanism including means providing a form to which a spring leaf may be shaped, two separate cable members mounted side by side for pressing the spring leaf to the shape of the means providing the form, and resiliently mounted equalizing means carrying said cable members. 75
10. A spring leaf forming mechanism including means providing a form to which a spring leaf may be shaped and cable means including two parallelly arranged cables mounted for pressing the spring leaf to the shape of the means providing the form, equalizing means located at the ends of the cables and adjusting means adapted to adjust the cables to various width springs. 80
11. A spring leaf forming mechanism including means providing a form to which a spring leaf may be shaped and cable means including two parallelly arranged cables mounted for pressing the spring leaf to the shape of the means providing the form, equalizing means located at the ends of the cables, adjusting means adapted to adjust the cables to various width springs and presser means adjustable lengthwise of the cables for pressing portions of the cables against said form means. 100
12. A spring leaf forming mechanism including the individually adjustable form elements 9 and the ball and socket cable means A for pressing a spring leaf to the shape of a form provided by said form elements. 110
13. A spring leaf forming mechanism including the adjustable form means 9, the ball and socket cable means A for pressing a spring leaf to the shape of said form means, and the yieldably mounted pressers 75 mounted for longitudinal adjustment relative to the cable means A for pressing the cable means against the spring leaf. 115
14. A spring leaf forming mechanism including the individually adjustable form elements 9, the ball and socket cable means A for pressing a spring leaf to the shape of a form provided by said form elements, and the tension means 64 and 80 which prevent breaking of the cable means A when forced toward said form elements. 125
- 65

15. A spring leaf forming mechanism including the adjustable form means 9, the cable means A including two ball and socket-like cables arranged side by side for pressing a spring leaf to the shape of said form means, and the equalizing means 61 to which the ends of the cable means A are secured.

5 In testimony whereof, I have signed my name to this specification.
